US00D970405S

(12) **United States Design Patent** (10) **Patent No.:** **US D970,405 S**
(45) **Date of Patent:** **** Nov. 22, 2022**

(54) **FENDER FLARE**

(71) Applicant: **Bushwacker, Inc.**, Buford, GA (US)

(72) Inventor: **Kyle Leppek**, Hoschton, GA (US)

(73) Assignee: **Bushwacker, Inc.**, Buford, GA (US)

(**) Term: **15 Years**

(21) Appl. No.: **29/769,590**

(22) Filed: **Feb. 5, 2021**

Related U.S. Application Data

(63) Continuation of application No. 29/668,091, filed on Oct. 26, 2018, now abandoned.

(51) **LOC (13) Cl.** **12-16**

(52) **U.S. Cl.**

USPC **D12/184**

(58) **Field of Classification Search**

(57) **CLAIM**

The ornamental design for a fender flare, as shown and described.

DESCRIPTION

FIG. 1 is a front perspective view of a fender flare, showing my new design;

FIG. 2 is a bottom rear perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

Broken lines are used to illustrate portions of the fender flare that form no part of the claimed design.

1 Claim, 6 Drawing Sheets
